UNITED STATES PATENT OFFICE.

SIDNEY RALPH SABEL, OF CHICAGO, ILLINOIS.

DUST-CAP FOR AUTOMOBILES.

1,397,235.

Specification of Letters Patent.

Patented Nov. 15, 1921.

Application filed July 5, 1921. Serial No. 482,310.

To all whom it may concern:

Be it known that I, SIDNEY RALPH SABEL, citizen of the United States, residing at Chicago, Illinois, have invented certain new and useful Improvements in a Dust-Cap for Automobiles; and I do hereby declare the following to be a full, clear, and exact description of the invention, such as will enable others skilled in the art to which it applies to make and use the same.

My invention relates to dust caps for shielding the exposed valve stems on pneumatic tires as used with automobiles or other vehicles. Generally speaking, it is the aim of my invention to provide an unusually simple and easily constructed and easily manipulated cap for this purpose, and to arrange the same so that the cap proper can be detached in a minimum of time and so that the detaching of this cap proper will not tend to loosen the portion of the device which supports the same. Furthermore, my invention aims to provide an appliance of this kind which will have no levers or fingers projecting beyond the cap proper, which will not require any lateral openings in the latter, and which will hold the cap proper firmly interlocked with the holder portion of the device without requiring an undue accuracy in the manufacture of the constituent parts. Still further and more detailed objects will appear from the following specification and from the accompanying drawings in which—

Figure 1 is an elevation of the cap proper or detachable portion of my appliance.

Fig. 2 is a corresponding elevation of the stationary portion of the appliance.

Fig. 3 is a central and vertical section through the assembled appliance.

Fig. 4 is a transverse section taken along the correspondingly numbered line of Fig. 3.

Fig. 5 is a plan view of the cap proper of Fig. 1.

Fig. 6 is a bottom view of the assembled appliance as shown in Fig. 3.

In the embodiment of the drawings, the appliance of my invention comprises a nipple 1 having at its bottom a female thread 2 adapted to be threaded upon the usual stem of a tire valve, and having a hexagonal base 3 disposed within a hexagonal collar 4 which has a contracted top 5 soldered to the base 3 of the nipple. Punched out of the nipple and projecting at opposite sides from the latter are a pair of spring tongues 5 each of which has its free end directed

downwardly or toward the base of the nipple and each of which tongues is normally directed outwardly after the manner of Fig. 3 by its own resiliency.

Slipped over the tubular stem of the nipple 1 is a companion member 7, or detachable cap portion, which consists substantially of an elongated thimble closed at its upper end and provided with a pair of outwardly directed recesses 8 adapted respectively to house the said tongues 6. Each of these recesses or niches desirably has an end wall 9 extending outwardly substantially radially of the axis of the cap and adapted to engage a lateral edge of the tongue 6 housed by the said recess. However, the outer wall of the recess slopes gradually into the cylindrical main wall portion of the cap at the other side of the niche or recess after the manner shown in Fig. 4, while the bottom of the recess is substantially horizontal so as to afford a ledge engaging the tip of the adjacent tongue when the detachable cap portion is in its normal position as shown in Fig. 3.

The nipple 1 or stationary portion of the appliances is made of some spring metal, so that each tongue normally is directed outwardly by its own resiliency without requiring any auxiliary spring, and so that each of the said tongues may be flexed inwardly when the detachable cap portion is to be withdrawn. This detaching is effected by partially rotating the detachable cap portion in a direction which is clockwise in Fig. 4, thereby causing the inner wall of each recess to act as a cam for forcing the adjacent spring tongue inwardly or into alinement with the main cylindrical wall of the nipple 1. When the detachable cap portion has thus been rotated sufficiently to swing the recess entirely to one side of the adjacent tongue, this cap portion can readily be slid off the end of the stationary nipple.

In replacing the detachable cap portion, the latter can readily be slipped from the free end of the nipple with the recesses in alinement with the spring tongues and slid longitudinally into position, as the cylindrical lower end 10 of the cap portion will force the spring tongues inwardly until this end portion clears the tip of the tongues, whereupon the resiliency of the tongues will cause these to snap into the recesses and lock the detachable cap portion in position. To prevent an unscrewing of the threaded por-

tion 2 from the valve stem when the detachable cap is detached, I preferably dispose the side wall 9 of each recess so that the partial rotation necessary for forcing the spring 5 tongues out of the recesses housing the same will be in a direction tending to screw the nipple more firmly upon the stem of the tire valve. I also desirably form each recess 8 with its exposed end wall 9 parallel to the 10 axis of the cap, and form each spring tongue with the corresponding edge, 14, in a plane axial of the cap, so that any attempt to rotate the cap in the wrong direction will cause the said edge of the tongue to engage the end 15 wall 9 of the niche along a considerable portion of its length, thereby preventing such an attempt from bending the tongue out of shape.

To insure a completely dust-proof closure, 20 I desirably insert a leather washer or gasket 13 in the hexagonal collar 4 and I may also employ a washer or gasket 12 between the bottom of the detachable cap and the top of the collar 4 after the manner shown in Fig. 25 3. By so doing, it will be obvious that my appliance provides an entirely sealed closure, as its construction requires no apertures whatever through which dust might filter in.

However, while I have heretofore 30 described my invention in a highly desirable embodiment including a hexagonal base portion and a gasket, I do not wish to be limited to these or other details of the construction and arrangement thus disclosed, it being obvious 35 that the same might be modified in many ways without departing from the spirit of my invention or from the appended claims.

I claim as my invention:

40 1. A dust cap for tire valves or the like, comprising a stationary tubular member and a detachable cap member sleeved upon the same, one of the said members having spring fingers directed toward the other member 45 and engaging shoulders on the latter, the latter member having cam surfaces adapted upon a partial rotation of the cap to flex the said fingers out of engaging relation to the shoulders to permit the detaching of the cap.

2. A dust cap for tire valves or the like, 50 comprising a stationary nipple equipped with spring fingers directed outwardly and rearwardly of the nipple, and a cap sleeved upon the nipple and having outwardly directed recess formations respectively housing 55 the fingers, each such recess having its rear wall normally engaged by the cap to prevent withdrawal of the latter from the collar, each recess having at one side an inner cam surface adapted upon partial rotation 60 of the cap to flex the adjacent finger out of engaging relation to the rear wall of the recess.

3. A dust cap for tire valves or the like, 65 comprising a stationary nipple threaded upon the stem of the valve and equipped with spring fingers extending outwardly and rearwardly of the nipple, and a cap sleeved upon the nipple and equipped with recesses 70 respectively housing the said fingers, each recess having its rear wall normally engaged by the adjacent finger and having its outer wall sloped for flexing the finger inwardly upon partial rotation of the cap in the direction tending to tighten the nipple on the 75 valve stem.

4. A dust cap for tire valves or the like, 80 comprising a stationary nipple threaded upon the stem of the valve and equipped with spring fingers extending outwardly and rearwardly of the nipple, and a cap sleeved upon the nipple and equipped with recesses 85 respectively housing the said fingers, each recess having its rear wall normally engaged by the adjacent finger and having its outer wall sloped for flexing the finger inwardly upon partial rotation of the cap in the direction tending to tighten the nipple on the valve stem, and each recess having a lateral 90 wall disposed for engaging an edge of the adjacent finger to prevent rotation of the cap in the opposite direction.

5. A dust cap as per claim 4, in which the 95 said lateral wall of each recess and the said finger edge are both disposed in planes radial of the axis of the cap.

Signed at Chicago, July 2nd, 1921.

SIDNEY RALPH SABEL.
